UNITED STATES PATENT OFFICE.

JULIUS ZÜHLKE, OF NEUWIED, GERMANY.

MEANS FOR MAKING WHEEL-RIMS.

SPECIFICATION forming part of Letters Patent No. 602,926, dated April 26, 1898.

Application filed February 4, 1897. Serial No. 622,015. (No model.)

To all whom it may concern:

Be it known that I, JULIUS ZÜHLKE, a subject of the German Emperor, residing at Neuwied, Germany, have invented certain new and useful Improved Means for Making Wheel-Rims, of which the following is a description.

This invention relates to improved means for producing a wheel-rim composed of a continuous grooved seamless annulus.

In carrying my invention into effect I form by pressure a hollow work-piece which corresponds in diameter to the diameter of the rim to be formed. This work-piece is grooved to assume the desired contour and is then cut up into narrow annular strips that constitute the rims.

In the accompanying drawings, Figure 1 is a sectional elevation of the machine for producing the rim; Fig. 2, a sectional plan thereof; Fig. 3, a cross-section on line B B, Fig. 1; Fig. 4, a similar section of the apparatus when arranged to make double rims; Fig. 5, a detail of disk d; Fig. 6, an end view of a single rim made by the machine; Fig. 7, a longitudinal section through a double rim, and Fig. 8 a transverse section through the double rim.

The letter c represents a hollow or cup-shaped body adapted to be slipped over the grooved cylindrical former or roller a of a lathe, the parallel grooves of the former corresponding to the profile of the rim to be formed.

The former a is secured to the live-spindle b, driven by step-pulleys or in other suitable manner. A sectional disk d, slipped into work-piece c and placed against its bottom c', serves to reinforce the work-piece and constitutes at the same time an abutment for the free end of the former, which bears directly against such disk. After the work-piece has been placed over the free end of the former a head d', fitted to a sliding or extensible spindle b', is by lever h advanced against the bottom c', so that the work-piece and the disk d are pressed tightly against the former.

The diameter of the work-piece should be greater than that of the former, so that it can be readily drawn off the same after being spun. The spindle b' is placed eccentrically to spindle b to produce while revolving a contact along one line between the former and the inner face of the work-piece, Fig. 2. Opposite to this line of contact there is secured to the machine-frame A, by means of a slide

e', a spinning-roll e, adapted to engage the work-piece and to spin or force it inward between the ribs of the former a. The slide e' is laterally movable upon its rest e² by means of a screw e³ or otherwise, so that roll e may 60 be brought into alignment consecutively with the different grooves of the former. The slide is of course also longitudinally movable, so as to permit the spinning-roll to be advanced toward or withdrawn from the work. The 65 roll can be of such size and configuration that a number or all of the profiles are shaped at one and the same time. After the work has been spun as described it is cut up into grooved annuli, Fig. 6, which are formed by 70 cutting through the center of each of the beads spun upon the work-piece. In this way each annulus is of the proper configuration to constitute a continuous grooved seamless wheel-rim.

If double rims are to be formed, a single hollow work-piece or cylinder f is first shaped with deep grooves f'. Around this is slipped a second hollow work-piece or cylinder g, and into this second work-piece shallow grooves 80 g' are spun. The cylinders are then cut up into annuli and the edges of every rim thus formed are intimately connected by a lap-joint, Fig. 8.

If desired, the hollow work-piece may be 85 first cut up into rings and may then be spun. The bottom c' may be utilized for different purposes.

What I claim is—

1. The process of forming a compound 90 wheel-rim which consists in forming a cylinder with deep grooves, surrounding it by a second cylinder, forming the same with shallow grooves, subdividing the telescoped cylinders into rings, and uniting the edges of 95 the rings, substantially as specified.

2. In a machine for forming wheel-rims the combination of a spinning-roll with a cylindrical former having a series of parallel grooves, and with a sectional disk d, adapted 100 to reinforce the bottom of the work-piece and to constitute an abutment for the free end of the former, substantially as specified.

In testimony whereof I have signed this specification in the presence of two subscribing witnesses.

JULIUS ZÜHLKE.
